HENRY R. SCHLUETER AND ALPHONSUS H. HATKE, OF RICHMOND, VIRGINIA.

MACHINE FOR ATTACHING PINS TO LEAVES.

Application filed September 21, 1926. Serial No. 136,883.

This invention relates to the art of preparing leaves for use in making wreaths and particularly to machines whereby the leaves may be attached to a pin or prong automatically so that these leaves may afterwards be assembled to form wreaths, garlands, or other "flower pieces."

Today in the preparation of wreaths and the like, leaves are attached by hand to pins or prongs. Usually the stems of the leaves are wired to the pins or prongs and then the pins may be inserted in a foundation composed of moss or like material until this base or foundation is covered with overlapping leaves. This takes time and more or less skilled labor and the general object of the present invention is to provide a machine which will automatically attach to the stem of a leaf or leaves an anchoring member or pin preferably in the form of an arrow which may be readily inserted within the moss base of the piece to be constructed.

Another object is to provide a mechanism of this character whereby a plurality of leaves in overlapping relation and each slightly off-set from the other may be connected by their stems to a common pin of sheet metal and provide means whereby the stems of a plurality of leaves may be cut off evenly to be engaged by the pin.

A further object is to provide a machine of this character in which the leaves are supported in a magazine and fed to the pin attaching mechanism and in which the pins are struck out of a strip of metal by dies and another object is to provide a machine in which the pins are formed with an arrow-shaped head and two legs at the rear end of the shaft, these legs being bent over and around the stems of a plurality of leaves to thus attach the leaves to the pins.

Our invention is illustrated in the accompanying drawings wherein:—

Figure 1 is a top plan view of an embodiment of our invention;

Fig. 2 is a side elevation thereof;

Fig. 3 is a longitudinal vertical sectional view of the machine;

Fig. 4 is a transverse sectional view on the line 4—4 of Figure 3;

Fig. 5 is a detailed plan view of the pin or "pick" forming die members;

Fig. 6 is a detailed sectional view showing the action of the pins or plungers 62;

Fig. 7 is a view of a portion of the metal strip out of which the pins or "picks" are formed by the die members;

Fig. 8 is a view in the nature of a diagram, showing how the leaves overlap.

Referring to these drawings it will be seen that we have provided a supporting frame designated generally 10 and which may be of any suitable construction. Mounted upon one end of the frame is the magazine 11 having longitudinally slotted side walls 12, the slots being designated 13. Operating over the bottom 14 of the magazine and longitudinally thereof is a follower 15, the front face of which is cut away at 16, this cut away portion extending downward for a predetermined distance and then downward and forward and being transversely concave. The follower is supported by the rollers 17 at the bottom of the follower and by pins 18 which extend laterally from the follower and engage in the slots 13. Slides 19 are mounted upon the exterior of the side walls and engage with said pins and cords or cables 20 are attached to these slides and pass over pulleys 21 mounted upon the sides of the magazine and extend downward and are attached to weights 22. Thus, the follower will be drawn toward the forward end of the magazine. The leaves A are disposed in this magazine with their stems upward.

Mounted upon adjustable brackets 23 on each side of the wall of the magazine is a shaft 24 carrying a pair of rubber rollers 24 which extend transversely across the front of the magazine just above the bottom thereof and the front of the magazine is provided with a cross bar 25 having downwardly extending resilient fingers 26.

Mounted upon the rollers 27 disposed immediately below the rollers 24 is an endless belt 28 which, at its opposite end, is supported upon a roller 29, the bearings 30 for which are supported in slots 31 in the frame and are longitudinally adjustable by means of the screws 32 so as to keep the belt 28 taut.

Mounted above the belt 28 are the forward and rear rollers 33 and 34 over which pass the endless belt 35. The lower flight of this endless belt approximates closely the upper flight of the belt 28 and both belts move in the same direction. There are a pair of upper belts 35 and a pair of lower

belts 28, the belts of each pair being spaced from each other, as shown in Figure 1. Disposed above the space between the belts and immediately rearward of the rollers 24 is a 5 platen 36. This is supported by two posts 37 extending upward loosely through transverse rods 38. Coiled compression springs 39 are disposed between the rods 38 and the platen and urge this platen downward. The 10 platen at its forward end is widened so as to form a triangular portion 40 which extends beneath the inner ends of the rollers 24.

Disposed between the upper and lower flights of the belt 28 rearward of the platen 15 is a wooden roller 41 having a width equal to the space between the two lower belts 28 and disposed above this wooden roller 41 is a cutting roller 42 mounted upon a transverse shaft 43 which is cut away at 44 at one 20 point and provided with a knife blade 45. This shaft 43 is supported at its ends in bearings 46 and compression springs 47 are disposed on each side of this bearing and yieldingly support the same and the tension 25 of these springs may be regulated by means of the screws 48, one for each bearing. The leaves which are discharged from the magazine and carried forward by the upper and lower belts have their stems cut off by the 30 knife 45.

Disposed rearward of the rollers 41 and 42 and above the space between the belts is the longitudinally extending platen 49 supported upon the posts 50 extending through 35 the transverse bars 51 carried by the frame of the machine, the platen being urged downward by the coiled compression springs 52. Disposed between the two lower belts 28 and operating in this space and beneath 40 the platen 49 are two rotatable dies 53 and 54, one being a male die and the other a female and operating between the contacting 45 faces of these dies is a strip of metal B which is mounted upon a reel or spool 55 supported in bearings on the frame of the machine. The strip of metal B has a width less than 50 the space between the pairs of belts and passes upward between guide rollers 56 and between the rotatable dies 53 and 54. These dies are so formed as to punch out from the metal strip arrow-like pins b, each of these pins, as shown in Figure 7, having a triangular head b' and laterally projecting lugs b'' which intersect the shaft of the arrow. 55

The leaves are fed downward from the magazine with their stems upward and, therefore, the stems of the leaves extend rearward as the leaves pass between and are carried along by the two pairs of belts 28 and 35. Immediately above the rotatable die 54 there is disposed a roller 57 mounted upon a shaft 58 supported in vertically movable bearings 59 which are urged downward by means of a coiled compression spring 60, the tension of which is adjustable by means

of the screw 61. It will be seen that the pin b has its head and lugs of the same width as the width of the strip so that when the pin is cut from the strip the remainder of the strip immediately around the pin will be 70 completely detached from the body of the strip and will fall downward while the pin itself will be carried upward and rearward by the roller 57 and brought into contact against the undersides of the leaves with the 75 lugs b'' on each side of the stems of the leaves.

Mounted upon the die 54 on each side of the recess within which the pin b is disposed are small plungers 62. The heads 63 of 80 these plungers as the die rotates engage with fixed cams 64 having inclined cam projections 65 and these cam projections 65 cause the plungers 62 on each side of the pin to be forced inward, thus turning the lugs b'' over 85 upon the stems, as shown in Figure 6, thus clipping the anchor or pin to the three stems. The two or three leaves whose stems have been attached to the anchor are now carried 90 rearward and discharged onto the downwardly extending chute 66.

It will be understood that, as before remarked, the leaves are placed in the magazine with their stems upward, the leaves being as far as possible of uniform size and such as are commonly used for forming wreaths. The leaves are drawn downward by the rollers 24 which frictionally engage the belt 28, and the leaves are drawn between the rollers 27 and rollers 24 and onto the 100 lower belt 28 and between the two belts 28 and 35. The leaves are disposed in overlapping relation to each other but out of exact alignment so that the leaves are offset, as shown in Figure 8, and thus it is 105 necessary to provide means for cutting the three stems by a single cutter so that the three stems will terminate at the same point. This is done by the cutter 45 which is driven with the roller 41 in turn driven by a gear 110 wheel 67.

Any desired means may be used for operating the several instrumentalities described. Thus, I have illustrated a motor operated shaft 68 carrying a worm 69 which operates a worm wheel 70 mounted upon a vertical shaft 71. This vertical shaft carries the beveled gear wheel 72 which meshes with a beveled gear wheel 73 mounted upon a longitudinal extending shaft 74. The beveled gear wheel 73 drives the gear wheel 67 through a gear wheel 75 mounted upon the shaft of the gear wheel 67. Mounted upon the shaft 74 is a gear wheel 76 which engages with a beveled gear wheel 53^a mounted upon the shaft supporting the die 54. Also mounted upon this shaft is a gear wheel 53^b which engages with a gear wheel 54 mounted upon the shaft carrying the die 54. Engaging the gear wheel 67 is a gear wheel 115 120 125 130

77 which meshes with a gear wheel 27^a on the shaft supporting the rollers 27 and this gear wheel 27^a in turn engages with a gear wheel 24^a on the shaft supporting the rollers 24. The rollers 34 are driven by means of a gear wheel 34^a carried by the shaft supporting the rollers 34 and meshing with the gear wheel 67. This gear wheel 67 meshes with a gear wheel 41^a on the shaft carrying the wood roller 41 and the gear wheel 41^a meshes with a gear wheel 42^a on the shaft which supports the knife roller 42.

Preferably a table 78 will be disposed below the upper flight of the belt 28, the belt traveling over this table and preferably the magazine will be provided with two longitudinally extending rods 79 spaced apart a sufficient distance to receive between them the stems of the leaves, thus preventing the stems from inclining to the right or to the left. These rods will be removable from the top of the magazine to permit the insertion of leaves therein. Preferably the bottom of the magazine will be inclined downward and centrally so as to hold the leaves properly centered and the rounded lower face of the follower will cause the lower tips of the leaves to be turned forward so that they may be easily engaged by the rubber rollers 24 and the leaves carried forward between the upper flight of belt 28 and the platen 36 and then beneath the lower flight of the belt 35.

Attention is particularly directed to the form or shape of the pin or "pick" used. It will be noticed that it is made with an arrow head. Heretofore difficulty has been experienced with the ordinary pins or picks on account of the fact that they have been liable to slip in and out of designs, whereas with our pick this is impossible, as the arrow head holds the leaves securely in the position in which they are placed in the wreath or design, and it is impossible for them to accidentally come out of the design.

I claim:—

1. In a machine for attaching pins to leaves, a leaf magazine, means for withdrawing leaves from the magazine, a knife operating to cut the stems of the leaves, means then operating to present a pin to the leaf stem, and means then operating to clip the pin upon the stem.

2. A machine for attaching pins to leaves including a leaf magazine, means for withdrawing leaves from the magazine, a knife operating to cut the stems of the leaves, means operating to cut a pin from a strip of thin metal and form opposed lugs on the pin, and means then operating to compress the lugs around the stem and discharge the leaf and the attached pin.

3. A machine for attaching pins to leaves including a leaf magazine, means acting to withdraw the leaves from the magazine in

overlapping relation to each other, means acting to cut through a plurality of overlapped stems to thereby render all the stems so cut of uniform length, and means then acting to present a pin to the stem and clip the pin thereon and discharge the leaf with the attached pin.

4. In a machine for attaching pins to leaves, a magazine for the leaves, means acting to withdraw the leaves in overlapping relation to each other, means then acting to cut through the overlapped stems of the overlapped leaves to thereby render all of the stems so cut of uniform length, means then acting to present a pin to the stems, and means then acting to clip the pin around the stems and discharge the leaves with the attached pin.

5. A machine for attaching pins to leaves including a leaf magazine, means acting to withdraw a plurality of leaves from the magazine in superposed overlapping relation to each other, means then acting to cut through the overlapped stems of said leaves to thereby render all of the stems so cut of uniform length, means operating to cut a pin from a strip of thin metal and form opposed lugs on the pin and present said pin to said stems, and means then acting to bend a portion of the pin around said stems and to discharge the leaves with the attached pin.

6. A machine for attaching pins to leaves including in its organization two coacting rotary dies formed to cut successive pins from a strip of metal passing between the dies and to form opposed lugs on each pin, means for feeding bunches of leaves having overlapping stems toward said dies, said dies acting to bring each pin into proper relation to the stems of the bunch of leaves, means then acting to bend the opposed lugs around the stems.

7. A machine for attaching pins to leaves including in its organization a leaf magazine, a follower sliding through the magazine, means at the upper end of the magazine for supporting the stems of the leaves against lateral movement, means for withdrawing the leaves from said magazine one by one in overlapped relation, weights urging the follower towards the discharge end of the magazine, a conveyor for the leaves so withdrawn, a cutter disposed in the path of movement of the conveyor and acting to cut the stems of the leaves in uniform length, and means disposed in the path of the conveyor for presenting a sheet metal pin to said stems and bending a portion of the pin around the stems.

8. A machine for attaching pins to leaves including in its organization a leaf magazine, the bottom of which is downwardly and medially inclined, a follower slidingly mounted within the magazine and formed to curve the tip end of a leaf forward and

downward, longitudinally extending guides between which the stems of the leaves are supported, a conveyor extending from the magazine, means for withdrawing leaves in 5 superposed relation from the magazine and discharging them onto the conveyor, means in the length of the conveyor for cutting off the stems of the leaves to cause all stems to be of uniform length, and means in the 10 length of the conveyor for presenting a sheet metal pin to the stems and crimping a portion of the pin upon the stems.

9. A machine for attaching pins to leaves including a magazine in which the leaves are 15 supported with their tips extending downward, and their stems upward, an upper pair of laterally spaced conveyor belts, a lower pair of laterally spaced conveyor belts, laterally spaced rollers disposed at the discharge 20 end of the magazine and engaging the forward faces of the leaves on each side of the middle thereof and withdrawing the leaves from the magazine onto the lowermost conveyor, a rotary stem cutter operating between the upper belts, a wheel disposed below the cutter and coacting therewith and operating between the lower belts, and means 25 operating in the space between the upper and lower pairs of belts acting to apply sheet metal pins to the stems of the leaves and crimp the pins thereon.

10. A machine for attaching pins to leaves including a leaf magazine open at one end and adapted to support leaves with their tips 35 downward and their stem extending upward, a gravity actuated follower in the magazine urging the leaves forward, a pair of endless belts extending horizontally from in front of the magazine with their upper flights coincident with the bottom of the magazine, the belts being laterally spaced from each other, a pair of upper endless belts laterally spaced from each other and disposed above the first named belts, driving rollers for supporting said belts, the lower flights of the second named pair of belts operating over the upper flights of the first named pair of belts, rollers laterally spaced from each other and disposed immediately in front of the magazine and withdrawing leaves therefrom and depositing said leaves upon the upper flights of the first named pair of belts, an upper and a lower roller disposed in the space between said pair of belts and between which the leaves pass, one of said rollers having a stem cutting knife, a pair of rotatable dies contacting with each other and disposed between the pairs of belts, a reel for supporting a strip of metal for passage between said dies, said dies being formed to cut pins of sheet metal from said strip, and one of said dies acting to carry the sheet metal pin so cut upward into position beneath the path of movement of the stems of the leaves and the dies being formed to produce a pin having laterally projecting lugs, laterally disposed plungers mounted upon said last named die and adapted when forced inward to crimp the lugs over the stems of a plurality of leaves, fixed cams with which said plungers engage as the die rotates, and a roller disposed above the last named die and acting to hold the stems against the die as the lugs are crimped.

produce a pin having laterally projecting lugs, and means acting to crimp said lugs over the stems of a plurality of leaves.

11. A machine for attaching pins to leaves including a leaf magazine open at one end and adapted to support leaves with their tips downward and their stems extending upward, a gravity actuated follower in the magazine urging the leaves forward, a pair of endless belts extending horizontally from in front of the magazine with their upper flights coincident with the bottom of the magazine, the belts being laterally spaced from each other, a pair of upper endless belts laterally spaced from each other and disposed above the first named belts, driving rollers for supporting said belts, the lower flights of the second named pair of belts operating over the upper flights of the first named pair of belts, rollers laterally spaced from each other and disposed immediately in front of the magazine and withdrawing leaves therefrom and depositing said leaves upon the upper flights of the first named pair of belts, an upper and a lower roller disposed in the space between said pair of belts and between which the leaves pass, one of said rollers having a stem cutting knife, a pair of rotatable dies contacting with each other and disposed between the pairs of belts, a reel for supporting a strip of metal for passage between said dies, said dies being formed to cut pins of sheet metal from said strip, and one of said dies acting to carry the sheet metal pin so cut upward into position beneath the path of movement of the stems of the leaves and the dies being formed to produce a pin having laterally projecting lugs, laterally disposed plungers mounted upon said last named die and adapted when forced inward to crimp the lugs over the stems of a plurality of leaves, fixed cams with which said plungers engage as the die rotates, and a roller disposed above the last named die and acting to hold the stems against the die as the lugs are crimped.

12. In a machine for attaching pins to the stems of leaves, a pair of rotatable dies, and means for feeding a strip of sheet metal between said dies, said dies being formed to cut from the strip of metal a pin having an arrow-shaped head having an extreme width equal to the width of the strip, a shaft, and a plurality of laterally projecting lugs having an extreme width equal to the width of the strip.

13. In a machine for attaching pins to the stems of leaves, a pair of rotatable dies, and means for feeding a strip of sheet metal between said dies, said dies being formed to cut from the strip of metal a pin having an arrow-shaped head having an extreme width equal to the width of the strip, a shaft, and a plurality of laterally projecting lugs having an extreme width equal to the width of the strip.

strip, one of said dies having laterally projecting spring retracted plungers adapted when forced inward to engage said lugs and bend them over upon the stem or stems of a leaf or leaves.

14. In a machine for attaching pins to leaves, a leaf magazine, means for conducting the leaves along a predetermined path, said means engaging the lateral margins of
10 the leaves but not the middle portion of the leaf or stem, means for withdrawing leaves from the magazine and disposing them upon

said conveyor, means for cutting the stems of uniform length, means for cutting pins from sheet metal and attaching the pins to the 15 stems of the leaves, and common means for driving said leaf feeding means, said conveyors, leaf cutting means, and the pin operating means.

In testimony whereof we hereunto affix 20 our signatures.

HENRY R. SCHLUETER.
ALPHONSUS H. HATKE.
